(57) **CLAIM**

I claim the ornamental design for a cup carrier, as shown and described.

DESCRIPTION

FIG. 1 is a top plan view of a cup carrier in an unfolded configuration (and the bottom view is a mirror image of the top plan view);

FIG. 2 is a front elevation view of the cup carrier thereof (and the rear elevation view is an identical image of the front elevation view);

FIG. 3 is a right side elevation view of the cup carrier thereof (and the left side elevation view is an identical image of the right side elevation view);

FIG. 4 is top plan view of the cup carrier of FIG. 1, shown in a folded configuration;

FIG. 5 is a front elevation view of the cup carrier of FIG. 1, shown in a folded configuration (and the rear elevation view of the folded arrangement is an identical image of the front elevation view of the folded arrangement);

FIG. 6 is bottom view of the cup carrier of FIG. 1, shown in a folded configuration;

FIG. 7 is an isometric view of the cup carrier of FIG. 1, shown in a folded configuration; and,

FIG. 8 is a right side elevation view of the cup carrier of FIG. 1, shown in a folded configuration (and the left side elevation view of the folded arrangement is a mirror image of the right side elevation view of the folded arrangement).

The longer-sized dash lines in the form of a cup depicts environmental subject matter and form no part of the claimed design. The medium-sized and shorter-sized dash lines depict portions of the cup carrier that form no part of the claimed design.
